UNITED STATES PATENT OFFICE.

WILLIAM D. SCOTT, OF MARTINS FERRY, OHIO.

AIR COLLECTING AND DELIVERING APPARATUS.

1,327,926.

Specification of Letters Patent. Patented Jan. 13, 1920.

Application filed January 9, 1919. Serial No. 270,274.

To all whom it may concern:

Be it known that I, WILLIAM D. SCOTT, a citizen of the United States of America, and resident of Martins Ferry, county of Belmont, and State of Ohio, have invented 5 certain new and useful Improvements in Air Collecting and Delivering Apparatus, of which the following is a specification.

This invention relates broadly to air 10 propelling apparatus, and more particularly to a fan or blower of that type or class commonly employed for creating a circulation of air in mines.

The primary object of the invention is to 15 provide a device, specially adapted as a ventilating apparatus for the passages of mines and the like, which has a relatively high degree of efficiency due to structural features that provide a maximum air-gathering 20 and delivering capacity with a minimum of air resistance and, consequently, with a minimum of driving power required in its operation.

In describing the invention in detail, reference 25 is herein had to the accompanying drawings, in which—

Figure 1 is a view of the invention partly in side elevation and partly in broken section;

30 Fig. 2 is a perspective view of the rotor; Fig. 3 is a vertical section of the casing, showing the rotor in front elevation with its front auxiliary blades removed;

35 Fig. 4 is an enlarged perspective view of the blade-carrying hub showing in side elevation a fan blade mounted thereon;

40 Fig. 5 is a front elevation of the hub carried by the rotor shaft, showing the oblique disposition of a blade with respect thereto; and—

Fig. 6 is an enlarged section of a modified form of blade.

Referring to said drawings, in which like 45 designating characters distinguish like parts throughout the several views—

A indicates generally a rotor casing which is approximately of cylindrical form and comprises vertically disposed end walls 1 and an arc-shaped inclosing wall 2 which is 50 supported by said end walls and which extends from the rear end of a flat base 3 to

a point 4 located a suitable distance above the horizontal axial plane of the casing. From the terminal point indicated to the front end of said base 3 the casing is open 55 providing in the front part of said casing a discharge opening 5 through which air collected within the casing A is discharged, as will hereinafter be described.

Located within said casing is a rotor, 60 generally designated by the letter B, the shaft 6 of which is mounted in suitable bearings, as 7, carried by supports 8 disposed outside the casing at opposite sides. Said rotor has an eccentric disposition with respect to the casing, being so located that the capacity of the space between the periphery of the rotor and the wall 2 and base 3 of the casing gradually increases from the front terminal point 4 of said wall to the 65 discharge opening 5. Located in the opposite end walls 1 of said casing are circular air-intake openings 9 which have a concentric disposition with respect to said rotor, said openings being of less diameter than 70 that of said rotor.

The rotor comprises the shaft 6 which has mounted thereon at a point midway between the end-walls 1 of the casing a plain circular plate 10. Rigidly mounted on said shaft at 75 opposite sides of, and at a spaced distance from, said plate 10 are two hubs 11 each of which carries a plurality of spaced radially disposed arms 12. Rigidly attached to each 80 of said radial arms 12 is the middle portion 85 of a fan or propeller blade 13 which is of approximately semi-circular form. Said blade is mounted with its curved edge outermost and with its straight chord-like edge adjacent to the hub 11. Each of said blades 90 crosses the shaft 6 in a diagonal direction, as shown most clearly in Fig. 3, and has one end thereof rigidly attached to the adjacent face of the plate 10 at a suitable distance inward from the periphery of the latter. 95 The opposite ends of each set of the blades are rigidly attached to the inner face of a circular ring-like plate 14 which has approximately the same external diameter as the plate 10 and which has a concentric arrangement with respect to said plate and the shaft 6. Said rings 14 are disposed 100

closely adjacent to the end walls 1 of the casing, and the internal diameters of said rings approximate the diameters of the intake openings 9 in said end-walls. The 5 openings in said rings register with said openings 9 so that said rings offer negligible obstruction to the entrance of air through said intake openings.

Interposed between each of the rings 14 10 and the adjacent face of the plate 10 near the peripheral edges thereof is a plurality of transverse horizontal auxiliary blades 15, as is clearly shown in Fig. 2. Said auxiliary blades have a substantially radial 15 position, but preferably have their inner edges inclined slightly in a forward direction, as is best shown in Fig. 1, to accelerate somewhat the delivery of air in a manner which will hereinafter be described.

20 While the ends of the blades 13 may be attached to the plate 10 and rings 14 in any suitable manner, it is preferred that each blade have its opposite ends bent to such an angle that it is disposed in a plane at a right angle to the shaft 6, as shown at 16 in Figs. 25 3 and 4. The opposite angularly disposed ends are then respectively secured to the plate 10 and adjacent ring 14 by means of bolts or rivets 17.

30 It will be observed that the rotor is divided by the plate 10 into two similar sides in which the blades are reversely inclined so that when it is rotated forward an equal suction is created at opposite sides for drawing 35 air into the casing through the intake openings 9. Thus, the device has a capacity equal to that of two separate fans each having the capacity of one side, and possesses the obvious advantage that the stresses imposed upon the two opposite sides are equalized, one side balancing the other. This 40 results in a smoothly and freely running structure which, in practice, possesses a maximum of efficiency with a minimum expenditure of driving power.

45 In the modification illustrated in Fig. 6, the lower or straight edge of the blade 13^a is turned outward at a suitable angle so that a flange 18 inclined toward the adjacent end 50 wall 1 of the casing is provided, such flange being designed to increase somewhat the air-gathering capacity of the blade. In like manner the curved or peripheral edge of the blade may be turned inward at a slight 55 angle, as shown at 19 in Fig. 6, to slightly increase the capacity of the blades for impelling collected air.

In practice, the rapidly rotating blades 13 at opposite sides of the division plate 10 60 produce a powerful suction for drawing air through the opposite intake openings 9 of the casing, whence they impel the indrawn air forward and direct it outward with

great force through the discharge opening 5 in the front of the casing. As the collected 65 air passes outward beyond the outer ends of said blades 13, it is caught by the transverse auxiliary blades 15. Said auxiliary blades not only serve to accelerate the discharge of air from the casing but to produce 70 a radial outward suction or pull which prevents air from becoming baffled about the axis of the fan, and consequently successfully circumvents objectionable churning of air. 75

What is claimed is—

1. An air collecting and delivering apparatus comprising a casing having an air-intake opening in each of its opposite sides and a discharge opening in the front wall thereof, and a rotor mounted within said casing, said rotor comprising a shaft, a pair of fans mounted on said shaft, each fan consisting of a plurality of approximately semi-circular blades disposed in upright radial positions with their chord-like edges diagonally crossing said shaft, a disk-like wall interposed between said fans and having the inner ends of said fan blades attached thereto, the blades of the opposite fans being reversely arranged so that each fan acts to draw air inward through the adjacent intake opening, a ring connecting the extreme outer ends of the blades of each fan, and transverse auxiliary blades interposed between each ring and the adjacent side of said disk-like wall. 90

2. An air collecting and delivering apparatus comprising a casing having an air-intake opening in each of its opposite sides and a discharge opening in the front wall thereof, and a rotor mounted within said casing, said rotor comprising a shaft, a pair of fans mounted on said shaft, each fan consisting of a plurality of approximately semi-circular blades disposed in upright radial position with respect to said shaft and having their chord-like edges diagonally crossing said shaft and extending approximately equal distances on each side thereof, a wall carried by said shaft between said fans and having the inner ends of said fan blades attached thereto, and a plate-like ring connecting the outer ends of the blades of each fan, the openings through said rings being in register with the adjacent intake openings. 110

3. An air collecting and delivering apparatus comprising a casing having an air-intake opening in each of its opposite sides and a discharge opening in the front wall thereof, and a rotor mounted within said casing, said rotor comprising a shaft, a pair of fans mounted on said shaft, each fan consisting of a plurality of blades of approximately semi-circular form disposed in posi- 120

tions with their chord-like edges diagonally crossing said shaft, each blade having an outwardly inclined flange on its chord-like edge and an inwardly inclined flange on its 5 curved edge, and a disk-like wall interposed between said fans and having the inner ends of said fan blades attached thereto, the blades of the opposite fans being reversely

arranged so that each fan acts to draw air inward through the adjacent intake opening. 10

In testimony whereof, I affix my signature in presence of two subscribing witnesses.

WILLIAM D. SCOTT.
